FREDERICK G. JELLISON
INVENTOR

WITNESS: *John Donavan*

BY *Victor J. Evans*

ATTORNEY

UNITED STATES PATENT OFFICE

FREDERICK G. JELLISON, OF ROWLEY, MASSACHUSETTS

DISPENSING DEVICE FOR DENTAL ALLOY AND MERCURY

Application filed July 23, 1928. Serial No. 294,761.

This invention relates to a dispensing device for dispensing simultaneously two or more ingredients from containers holding the same, the general object of the invention being to provide a base to which the containers are attached, with a rotary shaft in the base having pockets therein, one for each container whereby when the shaft is turned to a certain position, the pockets will be filled 10 with material from the containers and then, by giving the shaft a half turn, the pockets will empty themselves into suitable outlet means so that the materials will fall into a container placed under the outlet means and 15 the mixture will consist of certain amounts of materials from the first mentioned containers, according to the sizes of the pockets.

While the invention is mainly intended for use in dental laboratories and may be used 20 for handling alloy and mercury, it will, of course, be understood that it may be used for other purposes.

Another object of the invention is to provide means for regulating the size of one or 25 more of the pockets.

A still further object of the invention is to provide an agitator for one or more of the containers, with means for moving the same as the shaft is rotated.

30 This invention also consists in certain other features of construction and in the combination and arrangement of the several parts, to be hereinafter fully described, illustrated in the accompanying drawing and specifically 35 pointed out in the appended claim.

In describing the invention in detail, reference will be had to the accompanying drawing wherein like characters denote like or corresponding parts throughout the several 40 views, and in which:

Figure 1 is an elevation showing one form of the invention.

Figure 2 is an end view thereof.

Figure 3 is a top plan view.

45 Figure 4 is a section on line 4-4 of Figure 2.

In these views, the numeral 1 indicates a base which is formed with a tapered bore 2 and with sockets 3 in its upper part for receiving the lower ends of the containers 4

which hold the materials to be dispensed. For instance, one container may hold alloy and the other mercury. A port 5 connects each socket 3 with the bore and an object port 6 is formed in the lower part of the base under one of the ports 5, with a notch 7 in the wall of the port 6 which is located under the other port 5. A tapered shaft 8 is rotatably arranged in the bore and has a head 9, the inner face of which is grooved, as at 10, to receive a cam ring 11. This shaft is formed with the cups 12, one for each container, these cups registering with the ports 5 when the shaft has been turned by the fingers of the operator grasping the head 9. Thus some of the material in each container will pass through the port 5 into a pocket of the shaft and then by giving the shaft a half turn, the pockets will empty themselves into the port 6 and the notch 7 so that the two amounts of materials 70 will pass into a container placed under the device. Thus a certain amount of each of two or more materials will be dispensed each time the shaft is turned.

A set screw 13 is arranged in a threaded hole in the rear end of the shaft with its inner end extending into one of the pockets so that by adjusting this screw, the size of the pocket can be regulated. An agitator 14 is arranged in one of the containers 4 and is formed of wire coiled upon itself, with its limbs extending downwardly through the container with one limb bent and fastened to the base and its other limb bent and extending through a hole in the base, with its extremity engaging the cam ring 11 so that the agitator will be moved as the shaft is turned and thus the material in said container 4 will be agitated.

While the drawing shows the device with but two containers, it will, of course, be understood that the device can be made larger so that it can support a greater number of containers with their associated parts.

A screw 15 is connected with the base so that the device can be fastened to a suitable support.

It is thought from the foregoing description that the advantages and novel features 100

of the invention will be readily apparent.

It is to be understood that changes may be made in the construction and in the combination and arrangement of the several parts, provided that such changes fall within the scope of the appended claim.

What I claim is:—

A device of the class described comprising a base having a bore therein and ports in its upper portion communicating with the bore and an outlet port in its lower part arranged under the other ports, containers supported by the base and in communication with the upper ports and a shaft rotatably mounted in the bore and having pockets therein arranged to register alternately with the upper ports and the lower port during the rotation of the shaft so that some of the material in each container will drop into the pockets and then be discharged through the outlet port, an agitator in one of the containers having a part passing through a part of the base, a handle forming head on the outer end of the shaft and a cam on said head engaging said part of the agitator for moving the agitator when the shaft is turned.

In testimony whereof I affix my signature.

FREDERICK G. JELLISON.
